UNITED STATES PATENT OFFICE.

JOHN J. FLANIGAN, OF CHICAGO, ILLINOIS, ASSIGNOR TO DUPLICATOR MANUFACTURING COMPANY, OF CHICAGO, ILLINOIS, A CORPORATION OF WEST VIRGINIA.

DEVICE FOR TRUING UP THE ROLLS OF DUPLICATING-MACHINES.

1,317,487.

Specification of Letters Patent. Patented Sept. 30, 1919.

Application filed April 24, 1919. Serial No. 292,301.

To all whom it may concern:

Be it known that I, JOHN J. FLANIGAN, a citizen of the United States, residing at Chicago, in the county of Cook and State of Illinois, have invented certain new and useful Improvements in Devices for Truing Up the Rolls of Duplicating-Machines, of which the following is a specification.

In the use of multiple copying or duplicating machines of that type which employ a flat printing bed and a gelatin band overlying the bed and alternately wound between delivery and receiving rolls at opposite ends of the bed, as illustrated, for example, in my former Letters Patent No. 1,118,119, dated November 24, 1914, it frequently happens that the duplicating band is wound unevenly on the spindle of the winding-up roll; that is, the band tends to creep toward one end or the other of the spindle. When the rolls are reversed in the machine for re-use of the duplicating band, the latter as it unwinds fails to lie exactly true on the bed of the machine, and as it is wound up on the receiving roll, the end-wise creeping tendency is still further exaggerated.

One object of my present invention is to provide a simple, inexpensive and practical device in the nature of an accessory of the machine itself for truing up the rolls. On account of the sticky character of the duplicating band, an unevenly wound roll can not be corrected by simply pressing the roll end-wise on the spindle to bring the convolutions in exact superposition. Hence, the effect must be cured by rewinding, and the device of my present invention operates on this principle, utilizing certain parts of the duplicating machine itself to effect this rewinding.

Another object of the invention is to provide an improved means for moistening the rolls when they have become too dry.

The device of my invention, its mode of use, and the advantages flowing therefrom will all be readily understood and appreciated by those skilled in the art from the following description, taken in connection with the accompanying drawings, wherein—

Figure 1 is a top plan view of a multiple copying machine of the type illustrated in my former patent, above referred to, showing my present improvement mounted in working form thereon.

Fig. 2 is a side elevation, partly broken out, as viewed from the lower side of Fig. 1.

Referring to the drawings, 5 designates each of the parallel side frame members, and 6 the bed-plate of the machine frame, the bed-plate 6 being covered by a strip of cloth 7 stretched thereover and secured at each end by clamping strips 8. On the bed, in the regular use of the machine for copying, is stretched the duplicating band 9, the two ends of which are attached to spindles 10 and 11 at the forward and rear ends of the machine frame, respectively; the band 9 being guided over supporting and guiding rolls 12 and 13 at the front and rear ends of the bed, respectively, and the winding up spindle 10 being engaged with a winding chuck and operated by a chain and sprocket winding mechanism 14 actuated by a hand crank 15, all as fully described in my former patent above referred to. At one side of the machine frame is a longitudinal rod or bar 16 on which is mounted for both turning and sliding movement the platen carriage designated as an entirety by 17, this platen carriage being shown as swung upwardly and backwardly to facilitate the rewinding operation when a roll is to be trued up.

Coming now to those features with which my present invention is concerned, 18 designates as an entirety a low frame structure having substantially the form of a shallow rectangular pan that is adapted to rest directly on the printing bed of the machine. To the under side of the frame 18 are secured a pair of hooks 19 which engage over the rear guide roll 13 to resist the forward pull of the band during the rewinding operation. At the rear of the frame 18 and extending transversely thereof is a rail 20, and near the forward end of the frame 18 are a pair of upwardly and rearwardly inclined supports 21 for a pair of grooved rollers 22.

Above the frame 18 is a carriage consisting chiefly of parallel side bars 23, a rear cross-bar 24, and a front cross-rod 25. The rod 25 rests upon the rollers 22, while to the rear cross-bar 24 are secured a pair of depending legs 26 in which are journaled grooved rollers 27 resting upon the rail 20. It will thus be seen that the carriage has a wheel and track engagement with the underlying frame structure 18 and is movable crosswise of the latter with a minimum of friction.

Secured to and extending between the side bars 23 of the carriage is an intermediate cross-bar 28, and secured to the latter and to the rear cross-bar 24 are a pair 5 of hangers 29 which serve to removably support a rectangular water pan 30. In this pan dips the lower portion of a cloth covered moistening roll 31, the spindle of which is journaled in open bearings 32 formed in 10 the upper edge of the side bars 23 of the carriage. In the upper edges of these side bars are also formed oblique open bearings 33 to receive the spindle of the guide roll 37, which latter may conveniently be one of the 15 journals 33 adapted to receive the spindle of the roll 34 which is to be trued. Secured to the side bars 23 in rear of the bearings 32 are a pair of posts 35, in the upper ends of which are formed open bearings 36 to receive the spindle of a guide roll 37, which latter may conveniently be one of the 20 stock duplicating band spindles.

38 designates a guide block or strip that is adapted to overhang the forward guiding and supporting roller 12 and is adjustable lengthwise of the latter by means of a clamping screw 39 (Fig. 2) by which it is secured in fixed position to the forward edge of the bed-plate. This guide block or strip 38 is designed to mark a fixed position for one edge of the duplicating band during the 25 re-winding operation, the edge of the band passing in sliding contact with the guide strip. This device is preferably used in the re-winding operation, but is not indispensable since I have found that experienced operators are able to effect accurate re-winding and truing up by simply observing the position of one edge of the band relatively to the surface of the roller 12 over which the band passes just before it goes on to the 30 re-winding spindle. 40 designates a drip pan placed beneath the winding-up spindle to catch any superfluous moisture that may fall from the roll during the re-winding operation.

45 In the use of the device, when an unevenly wound roll is to be trued up, the platen frame 17 is thrown back out of the way, the frame with the carriage resting thereon is placed on the bed of the machine with the 50 hooks 19 engaged behind the rear guide roll 13, as clearly shown in Fig. 2, water is placed in the pan 30 in sufficient amount to submerge the lower portion of the moistening roll 31, the roll 34 to be trued is set in the 55 bearings 33, and the free end of the band, to which the empty winding up spindle is attached, is passed over the moistening roll 31, then over the guide roll 37, then forwardly down over the forward guiding and 60 supporting roll 12 of the machine, and the spindle is entered in the winding chuck. The guide block 38, if used, is then adjusted into contact with the edge of the band, and the operator grasps the crank 15 with one 65 hand and the carriage frame with the other

and proceeds to re-wind the band. During the re-winding the carriage is shifted cross-wise sufficiently to always maintain one edge of the band in sliding contact with the guide block 37 or at a fixed position on the surface of the roller 12, so that the band is wound up evenly on the spindle 10 with the successive turns or coils in accurate superposition. The band passing in contact with the surface of the roll 31 is given the necessary additional moisture to prevent the band from drying out and to maintain it in good working condition. 70

I have found that operators of this device soon become exceedingly expert and are able 80 to true up an unevenly wound roll in but a few seconds of time. One advantage of this device resides in the fact that the duplicating machine itself may be used in co-operation with the described attachment or 85 accessory to effect the purpose of the invention.

Manifestly the device shown and described may be modified in detail to a considerable extent without involving any departure from 90 the principle of operation or sacrificing any of the advantages secured. Hence I reserve all such variations and modifications as fall within the spirit and purview of the appended claims. 95

I claim:

1. A device for truing up the rolls of a duplicating machine by rewinding, comprising, in combination, a carriage adapted to be supported on the duplicating machine 100 and movable crosswise of the latter, said carriage having journals for the spindle of the roll to be trued, and means for guiding the duplicating band edgewise as the latter passes from said roll to the rewinding 105 spindle.

2. A device for truing up the rolls of a duplicating machine by rewinding, comprising, in combination, a carriage adapted to be supported on the duplicating machine 110 and movable crosswise of the latter, said carriage having journals for the spindle of the roll to be trued, and a support for the duplicating band as the latter travels from the said roll to the rewinding spindle. 115

3. A device for truing up the rolls of a duplicating machine by rewinding, comprising, in combination, a carriage adapted to be supported on the duplicating machine 120 and movable crosswise of the latter, said carriage having journals for the spindle of the roll to be trued, and a guide adapted to engage an edge of the duplicating band as the latter travels from the said roll to the rewinding spindle. 125

4. A device for truing up the rolls of a duplicating machine by rewinding, comprising, in combination, a carriage adapted to be supported on the duplicating machine 130 and movable crosswise of the latter, said

carriage having journals for the spindle of the roll to be trued, a support for the duplicating band, and a guide adapted to engage an edge of the duplicating band as the latter travels from the said roll to the rewinding spindle.

5. A device for truing up the rolls of a duplicating machine by rewinding, comprising, in combination, a carriage adapted to be supported on the duplicating machine and movable crosswise of the latter, said carriage having journals for the spindle of the roll to be trued, a support for the duplicating band as the latter travels from the 10 said roll to the rewinding spindle, a guide for one edge of the duplicating band adjustable lengthwise of said support, and means for securing said guide in any adjusted position.

20 6. A device for truing up the rolls of a duplicating machine by rewinding, comprising, in combination, a carriage adapted to be supported on the duplicating machine and movable crosswise of the latter, said carriage 25 having journals for the spindle of the roll to be trued, means for guiding the duplicating band edgewise as the latter travels from said roll to the rewinding spindle, and means for moistening said band during its 30 travel to the rewinding spindle.

7. In a duplicating machine accessory for the purpose described, the combination of a frame structure adapted to rest on the bed of the machine, a carriage mounted on and 35 movable crosswise of said frame structure, said carriage having journals for the spindle of the roll to be trued, and means for guiding the duplicating band edgewise as the latter travels from said roll to the rewinding 40 spindle.

8. In a duplicating machine accessory for

the purpose described, the combination of a frame structure adapted to rest on the bed of the machine, a carriage mounted on and movable crosswise of said frame structure, 45 said carriage having journals for the spindle of the roll to be trued, a moistening roll mounted on said carriage, means for directing the band in contact with said moistening roll, and means for guiding the band 50 edgewise as the latter travels from said moistening roll to the rewinding spindle.

9. In a duplicating machine accessory for the purpose described, the combination of a frame structure adapted to rest on the bed 55 of the machine, a carriage mounted on and movable crosswise of said frame structure, said carriage having journals for the spindle of the roll to be trued, a moistening roll mounted on said carriage, a guide roll journaled on said carriage and serving to direct the band in contact with said moistening roll and means for guiding the band edge- 60 wise as the latter travels from said guide roll to the rewinding spindle. 65

10. In a duplicating machine accessory for the purpose described, the combination of a frame structure adapted to rest on the bed of the machine, a carriage having wheel and track engagement with said frame 70 structure and movable crosswise of the latter, said carriage having journals for the spindle of the roll to be trued, a water pan mounted on said carriage, a moistening roll dipping in said pan, a guide roll journaled 75 on the said carriage and serving to direct the band in contact with said moistening roll, and means for guiding the band edge- wise as the latter travels from said guide roll to the rewinding spindle.

JOHN J. FLANIGAN.
